UNITED STATES PATENT OFFICE

SERN MADSEN, OF CLINTON, IOWA, ASSIGNOR TO CURTIS COMPANIES, INCORPORATED, OF CLINTON, IOWA, A CORPORATION OF IOWA

SPRING HUNG SASH CONSTRUCTION

Original application filed March 24, 1930, Serial No. 438,451. Divided and this application filed April 14, 1930. Serial No. 444,189.

The object of my invention is to provide a spring means for hanging the sashes of window frames, the construction being simple, durable and inexpensive.

5 A further object is to provide springs instead of sash cords and weights for counter-balancing the sashes of windows, the parts being so arranged that the springs and sashes are easily assembled relative to the window 10 and can be easily renewed if desired.

Another object is the elimination of window weights and the necessary boxes therefor whereby a narrower window trim can be used which lends to the architectural beauty 15 of the construction.

A further object is to provide straight line extension springs for suspending the window sashes, the side jambs, side stiles of the sash and the window stops cooperating with each 20 other to house the springs.

With these and other objects in view my invention consists in the construction, arrangement and combination of the various parts of my spring hung sash construction, 25 whereby the objects contemplated are attained, as hereinafter more fully set forth, pointed out in my claims, and illustrated in the accompanying drawings, in which:

Figure 1 is an outside elevation of a window frame showing the left hand side thereof with parts broken away and with other parts shown in section to illustrate the invention fully.

Figure 2 is a similar view of the right hand window frame as viewed from the inside of a building.

Figure 3 is a vertical, sectional view on the line 3—3 of Figure 1.

Figure 4 is a horizontal, sectional view on 40 the line 4—4 of Figure 1; and

Figure 5 is a similar horizontal, sectional view illustrating a slightly modified form of construction.

My present application has to do with a 45 novel spring suspension for window sashes,

which construction is claimed per se, and the present application is a division of my co-pending application, Serial Number 438,451, filed March 24, 1930, claiming the combination of spring hung sashes and a resilient 60 parting bead to compensate for the differential in spring tension.

On the accompanying drawings I have used the reference numeral 10 to indicate a sill of a window frame A. The head jamb of the 55 window frame A is indicated at 12 and the side jambs thereof at 14. An upper sash is indicated at B and a lower sash at C.

The sashes B and C are slidably mounted relative to the window frame A between blind 60 stops 16, parting stops 18 and inner stops 20 in the ordinary manner. Instead of providing the usual sash cords, weight pulleys, weights and weight boxes for the window frame, I eliminate all of these elements and 65 provide a pair of straight line extension springs 30 and 32 for the upper sash B and lower sash C respectively.

The side jambs 14 are provided with channels 34 and 36 to partially receive the springs 70 30 and 32 respectively.

The window sashes B and C are provided with channels 38 and 40 at the corners of the side stiles where the blind stop 16 is provided with a channel 42 and the inner stop with a 75 channel 44 as best shown in Figure 4 of the drawings. The channels 34, 38 and 42 conjointly house the spring 30, while the channels 36, 40 and 44 conjointly house the spring 32.

The upper ends of the springs 30 and 32 are secured to the side jambs 14 by means of screws 46 and 48. The lower ends of the springs 30 and 32 are secured to the window sashes B and C by screws 50 and 52 or other 85 suitable means. The tension of the springs 30 and 32 is preferably designed to balance the weight of the sashes B and C vertically midway of the window frame A.

Accordingly, the lower ends of the springs 90

may be secured to the window sashes, as shown, or at any points between the tops and bottoms of the sashes to suit the spring tension required to best balance the sashes.

- 5 Thus, when the sashes are moved above such midway position they will be moved against their weight which tends to lower them, while when moved below such midway position they will be moved against the tension of the spring
 10 which tends to raise them. Thus, a differential in the action of the springs is encountered, which must be overcome to prevent the sashes from moving freely to the central position and to retain the sashes in any position to
 15 which they may be adjusted.

To retain the sashes in any adjusted position the parting stop 18 may be replaced by one of resilient construction as illustrated in my co-pending application above referred to, 20 or other resilient devices may be used for frictionally engaging the sashes to prevent their free sliding movement.

On the other hand, manually actuated locking devices, such as spring pressed pins, 25 usually provided in connection with windows which do not have counter-balancing weights, may be used in the ordinary manner.

In Figure 5 I have illustrated a slightly modified form of spring suspension for the 30 window sashes B and C in which the channels 38 and 42 are substantially the same, except a little deeper, while the channels 34 and 36 in the side jambs 14 are somewhat wider.

The springs 30 and 32 have more room in 35 which to operate and extend at a slight angle as illustrated. The blind stops 16 and the inner stops 20 instead of being provided with grooves 42 and 44 as previously described, are merely cut at a slight angle as illustrated at 40 42a and 44a respectively. Thus, the springs are housed by the grooves in the jambs and sashes and by one surface of each stop.

This construction does not interfere with 45 advantages of the channel construction described in the first four figures of the drawings.

Certain advantages arise from forming the 50 grooves for housing the springs 40 and 42 conjointly in the jambs, the corners of the sashes and using the stops with or without grooves as part of the housing for the spring. When it is desired to remove a spring, a stop (which may be screwed or otherwise secured to the 55 side jambs 14 as by screws 46) is first removed and the ends of the springs are then unhooked from the screws 46 and 50 or 48 and 52.

This construction also provides an easy way 60 of removing the sashes for any purpose. After the springs are removed the sashes can be merely pulled out of the window frame. Thus, by having the grooves for the springs formed in the corners of the sashes rather than having half circle grooves in the sashes and side jambs, the springs do not form keys 65 to prevent removal of the sash.

Utilizing the stop to form part of the housing for the spring besides providing easy access to the spring also provides the most complete housing arrangement for the springs when exposed above the upper rails of the window sashes as is evident from an inspection of Figure 3, and reduces the exposure of the spring to a minimum consistent with the advantages above pointed out for replacing springs and removing sashes from the window frame.

The springs are much more easily replaced than sash weights of other constructions. It is believed, however, that the springs will last indefinitely and will not need replacement.

The spring housings formed by the stops 16 and 20 and the grooves 30, 32, 34 and 36 are preferably substantially greater in size than the springs themselves so that when one end of the spring is attached to the jamb and the other end is attached to the sash, the spring will extend diagonally, as shown in Figure 5. Thus the central portion of the spring, which would have most vibration during movements of the sash would be substantially midway between the sides of the housing. This prevents undesired spring noises and is one of the important features of the invention.

To eliminate the possibility of any water collecting back of the blind stops 16 I provide a notch 48 cut through from the outside of the blind stop to the back thereof or into the groove 42 as the case may be. Any water getting into the spring housing back of the blind stop will drain out over the sill 10 which is sloping.

Some changes may be made in the construction and arrangement of the parts of my device, without departing from the real spirit and purpose of my invention, and it is my intention to cover by my claims, any modified forms of structure or use of mechanical equivalents, which may be reasonably included within their scope.

I claim as my invention:—

1. The combination of a window frame having jambs and stops with a sash arranged to slide in the frame, said sash, jambs and stops each having a groove therein whereby to conjointly house springs, springs housed in said grooves and respectively connected to the sash and the frame, whereby removal of the stops from the window frame will permit the springs to be disconnected and removed laterally without disturbing the sash, large grooves may be provided without undue weakening of the sash, ample stock may be left for installation of a weatherstrip in the most desirable location therefor and whereby to permit insertion or removal of the sash relative to the window frame with said springs in operative connection with said sash and said frame.

2. A window frame having jambs and

stops, a sash slidably mounted in said frame, balancing springs attached to said frame and to said sash, said sash and said jambs having opposing grooves adjacent the face of the sash and adjacent said stops whereby to form housings for said springs, said housings being thus closed by said stops whereby removal of said stops permits lateral removal of said springs without removing said sash and whereby said sash may be moved into or removed from said frame with said springs in operative connection with said sash and said frame.

3. A window frame having jambs and stops, a sash slidably mounted in said frame, balancing springs attached to said frame and to said sash, said sash and said jambs having opposing grooves adjacent the face of the sash and adjacent said stops whereby to form housings for said springs, said housings being thus closed by said stops whereby removal of said stops permits lateral removal of said springs without removing said sash and whereby said sash may be moved into or removed from said frame with said springs in operative connection with said sash and said frame, said grooves in said jambs extending laterally beyond the face of the sash to thereby provide greater space between said jambs and said sash for lateral removal or insertion of said springs when said stops are removed.

4. The combination of a window frame having jambs and stops with a sash arranged to slide in said frame, springs operatively connected at their ends with said frame and said sash, said sash having grooves to form housings for said springs conjointly with a face of each jamb and a side of each stop, said housings being thus closed by said stops whereby removal of said stops permits lateral removal of said springs without removing said sash.

5. The combination of a window frame having jambs and stops with a sash arranged to slide in the frame, said sash, jambs and stops each having a groove therein whereby to conjointly house counterbalancing means, elongated resilient counterbalancing means housed in said grooves and respectively connected to the sash and the frame, whereby removal of the stops from the window frame will permit the counterbalancing means to be disconnected and removed laterally without disturbing the sash, large grooves may be provided without undue weakening of the sash, ample stock may be left for installation of a weatherstrip in the most desirable location therefor and whereby to permit insertion or removal of the sash relative to the window frame with said counterbalancing means in operative connection with said sash.

6. A window frame having jambs and stops, a sash slidably mounted in said frame, elongated counterbalancing means attached to said frame and to said sash, said sash and

said jambs having opposing grooves adjacent the face of the sash and adjacent said stops whereby to form housings for the counterbalancing means, said housings being thus closed by said stops whereby removal of said stops permits lateral removal of said counterbalancing means without removing said sash and whereby said sash may be moved into or removed from said frame with said counterbalancing means in operative connection with said sash.

7. A window frame having jambs and stops, a sash slidably mounted in said frame, counterbalancing means attached to said frame and to said sash, said sash and said jambs having opposing grooves adjacent the face of the sash and adjacent said stops whereby to form housings for said counterbalancing means, said housings being thus closed by said stops whereby removal of said stops permits lateral removal of said counterbalancing means without removing said sash and whereby said sash may be moved into or removed from said frame with said counterbalancing means in operative connection with said sash, said grooves in said jambs extending laterally beyond the face of the sash to thereby provide greater space between said jambs and said sash for lateral removal or insertion of said counterbalancing means when said stops are removed.

8. The combination of a window frame having jambs and stops with a sash arranged to slide in said frame, counterbalancing means operatively connected at their ends with said frame and said sash, said sash having grooves to form housings for said counterbalancing means conjointly with a face of each jamb and a side of each stop, said housings being thus closed by said stops whereby removal of said stops permits lateral removal of said counterbalancing means without removing said sash.

9. The combination of a window frame having jambs and stops with a sash arranged to slide in said frame, springs to balance said sash, opposing vertical grooves in the jambs and sash adjacent one face of the sash whereby to form in conjunction with each other housings for said springs, such housings being substantially greater in size than said springs whereby said springs may each be attached at one of its ends to a jamb and at its other end to said sash and extend at an angle relative to its housing whereby the intermediate portions of said springs will remain free from contact with the sides of said grooves to prevent noises during movement of the sash.

10. The combination of a window frame having jambs and stops with a sash arranged to slide in said frame, springs to substantially balance the sash secured at their upper ends to the jambs and at their lower ends to the sash, said structure having vertical grooves

providing spaces for the springs between the jambs and the sash, the springs being inclined from the axes of the grooves and of less diameter than the spaces afforded by the 5 grooves whereby the intermediate portions of the springs may remain free from contact with the sides of the grooves to avoid noises during movement of the sash.
